UNITED STATES PATENT OFFICE.

WILFRED H. BUTCHER, OF BURWELL, NEBRASKA.

VENT FOR WELL-PUMPS.

1,190,102.

Specification of Letters Patent.

Patented July 4, 1916.

Application filed March 20, 1915. Serial No. 15,931.

To all whom it may concern:

Be it known that I, WILFRED H. BUTCHER, a citizen of the United States of America, residing at Burwell, in the county of Garfield 5 and State of Nebraska, have invented new and useful Improvements in Vents for Well-Pumps, of which the following is a specification.

This invention relates to improvements in 10 vents for well pumps.

In carrying out the present invention, it is my purpose to provide a vent valve for well pumps whereby the pump casing will be relieved of the water contained therein succeeding the pumping operation so as to prevent freezing of the water in the pump casing and the resultant damage to the pump structure.

It is also my purpose to provide a vent 20 valve of the class described which will operate efficiently and effectively for its intended purpose and which will open automatically when the pump plunger is stopped so as to relieve the casing of the water 25 trapped therein and which will be automatically closed when the pump is brought into action so that the water may be drawn from the well to the surface of the ground through the pump casing.

With the above and other objects in view, the invention consists in the construction, combination and arrangement of parts hereinafter set forth in and falling within the scope of the claim.

In the accompanying drawing, the figure 35 is a vertical sectional view through a well pump equipped with a vent valve constructed in accordance with the present invention.

Referring now to the drawing in detail, 1 40 designates a pump barrel or casing sunk into the ground and having the lower end thereof disposed within the well and the upper end arranged above the surface of the ground. 2 indicates the plunger rod mounted within the barrel or casing 1 and capable of rectilinear movement to operate the plunger to force the water from the well upwardly through the pump barrel.

In accordance with my present invention, a by-pass casting 3 is secured to the barrel or casing 1 adjacent to the lower extremity thereof and the pump barrel 1 adjacent to the lower extremity of the by-pass casting is closed by means of a plug 4 so that the water drawn from the well in the operation of the pump will be diverted into the by-pass and

so caused to travel through and then into the barrel 1 above the plug 4, the water being delivered at the surface by the upper end of the pump casing. Formed in the 60 lower horizontal limb of the by-pass casting 3 is a vent opening 5 and disposed within such opening and normally closing the latter is a vent valve 6. Upstanding from the lower surface of the horizontal portion of 65 the by-pass casting is a bearing bracket 7 and pivoted between its ends in the bracket 7 is a lever 8. One end of the lever 8 is pivotally connected to the vent valve 6 while secured to the remaining end of such lever 70 and uprising therefrom and disposed within the vertical portion of the by-pass is a stem 9 while slidably mounted within the vertical portion of the by-pass is an actuating element 10 normally resting upon the stem 75 9 and holding the valve 6 in open position and movable upwardly within the vertical portion of the by-pass as the water is pumped through the latter to release the lever 8 and so permit the valve 6 to gravitate 80 to closed position.

In practice, while the pump is out of service, the element 10 is at the lower end of the vertical portion of the by-pass and in engagement with the stem 9 and holds the vent 85 valve 6 out of the vent opening 5, while when the pump is placed in operation and the water forced through the by-pass the actuating element 10 is moved upwardly 90 within the by-pass under the action of the flowing water, thereby releasing the valve 6 and permitting the latter to gravitate to closed position so as to prevent the escape of water from the casing while the pump is in use. When the pump is stopped, the element 10 settles in the water trapped in the 95 pump and opens the valve 6 with the effect to release the water so as to prevent freezing of the pump.

While I have herein shown and described the preferred form of my invention by way of illustration, I wish it to be understood that I do not limit or confine myself to the precise details of construction herein described and delineated, as modification and 105 variation may be made within the scope of the claim without departing from the spirit of the invention.

I claim:

A pump casing, a by-pass in said casing 110 adjacent to the lower end thereof having the lower portion formed with a vent opening,

a valve for closing said opening, a bracket in said by-pass adjacent to said vent opening, a lever fulcrumed between its ends to said bracket and having one end connected 5 to said valve, a stem secured to the other end of said lever and projecting upwardly therefrom, an actuating element slidably mounted within the vertical portion of said by-pass and bearing upon the upper end of 10 said stem to hold said valve in open posi-

tion and movable by the water flowing through the by-pass to disengage said stem whereby said valve may gravitate to closed position.

In testimony whereof I affix my signature 15 in presence of two witnesses.

WILFRED H. BUTCHER.
